UNITED STATES PATENT OFFICE

100,496

DESIGN FOR A REFRIGERATOR

William C. Grunow, River Forest, E Donald Coots, Oak Park, and Mahlon W. Kenney, Chicago, Ill., assignors to General Household Utilities Company, Chicago, Ill., a corporation of Delaware

Application March 18, 1935, Serial No. 55,928

Term of patent 14 years

To all whom it may concern:

Be it known that we, William C. Grunow, E Donald Coots, and Mahlon W. Kenney, citizens of the United States, residing at River Forest, Cook County, Illinois; Oak Park, Cook County, Illinois, and Chicago, Cook County, Illinois, respectively, have invented a new, original, and ornamental Design for a Refrigerator, of which the following is a specification, reference being had to the accompanying drawing, forming a part thereof.

The figure is a perspective view of the refrigerator showing our new design.

We claim:

The ornamental design for a refrigerator, as shown.

WILLIAM C. GRUNOW.
E. DONALD COOTS.
MAHLON W. KENNEY.
